METHOD AND MEANS FOR HANDLING METERED PERMIT MAIL

Application filed January 2, 1929. Serial No. 329,783.

This invention relates to a method and means for handling permit metered mail which operates to the advantage and convenience of both the postmaster and official mail handlers and the mailer or metered permit holder.

Under the "conditions upon which mailings of certain matter will be accepted under permit without stamps affixed as provided by section 452, Postal Laws and Regulations," clause 4, paragraph C, "the matter, regardless of its class or kind of device used in printing the indicia, must be presented at the post office or station thereof designated by the postmaster. . . . In a few unusual situations where it seems to be advantageous to the post office itself, certain 'pick-up' arrangements exist . . . where such cases exist . . . 'the pick-up' privilege may be continued in the discretion of the department under such arrangements and precautions as may be prescribed in each case, but in no instance may the matter be picked up unless turned over to the 'pick-up' carrier by the mailer, or his representative, together with the statement of mailing provided for herein."

In compliance with such regulations either the mailer, or his representative, is required to present the matter at a post office, or station designated by the postmaster or a "pick-up" carrier is required to attend the mailer.

Among the objects of my invention is to provide a method and means which will expedite the handling and dispatch of permit metered mail; to provide for the placement of such mail by the mailer accompanied with the required mailing statement directly into the custody of the postal authorities upon posting at any authorized depository for delivering to the postmaster by any authorized collector, and to provide for the transmission of the mail matter, as received by

the postmaster directly to the so called railway mail service.

To the above purposes my invention consists in the novel steps in a method of handling metered permit mail and the novel construction, arrangement and combination of parts of a mailing package for the practice of steps of the method as hereinafter fully, clearly and concisely described, definitely pointed out in my claims and illustrated by the accompanying drawings, (2 sheets), in which—

Fig. 1 is an elevation of the face, or address side, of a package, for use in the practice of my method and invention.

Fig. 2 is a longitudinal sectional elevation of the package and mailing statement taken on the line 2—2 of Fig. 3.

Fig. 3 is an elevation of the back of the package, showing the means for transmitting the mailing statement from the permit holder to the postmaster.

Fig. 4 is a view similar to Fig. 1, showing a modified, or alternative, form of the package.

Fig. 5 is an elevation showing the back of the package shown in Fig. 4.

Fig. 6 is an elevation representing the mailing statement.

Fig. 7 is a transverse sectional elevation taken on the line 7—7 of Fig. 5.

Referring to the drawings, by numerals, 10 designates the container for the mail matter, which in the form shown is an ordinary, commercial envelope, having a flap 11 and means, such as the metallic fastener 12 for securing the flap to the envelope body.

On the face of the envelope there is indicia 13 limiting the use of the package to metered permit mail; indicia 14 providing for designation of the number and destination of contained mail pieces; indicia 15 providing for the identification of the permit holder, or mailer; indicia 16, providing for the address of the postmaster; indicia 17 providing offi-

of mailing, one end of which is adapted to extend into said slot and the other end of which is adapted to be secured to said flap when the latter is closed, there being perforations formed in said statement of mailing to permit this to be torn off and removed from said slot by the proper authority.

7. In combination, a relatively large envelope having an opening; a flap adapted to fold against the back of said envelope to close said opening, there being a slot in said container spaced from said flap; a smaller envelope, one end of which is adapted to be positioned relative to said big envelope by extending into said slot; and a clasp for securing the other end of said small envelope and said flap to said big envelope, said small envelope being quickly detachable from said clasp.

29 In testimony whereof, I hereunto affix my signature this 29th day of December, 1928.

RALPH G. WHITLOCK.
